United States Patent Office

Des. 195,626
Patented July 9, 1963

195,626

PLAQUE

Sylvia H. Hood, 527 S. Fair Oaks, Pasadena, Calif.

Filed Oct. 21, 1957, Ser. No. 48,199

Term of patent 14 years

(Cl. D29—23)

The FIGURE is a front view of a plaque showing my new design. The plaque is of conventional thickness.

I claim:

The ornamental design for a plaque, as shown and described.
